UNITED STATES PATENT OFFICE.

LUTHER J. KIGER, OF NASHVILLE, TENNESSEE, ASSIGNOR TO NATIONAL AUTO TAG SEAL CORPORATION, OF NASHVILLE, TENNESSEE, A CORPORATION OF TENNESSEE.

LICENSE-TAG SEAL.

Application filed May 17, 1928. Serial No. 273,502.

The present invention relates to improvements in license tag seals and has reference more particularly to improvements over my prior Patent, No. 1,636,778, granted July 5 26, 1927.

One of the important objects of the present invention is to provide a license tag seal wherein the same includes an identification tag holder that is encased within a trans-10 parent housing so that the indicia on the identification card may be readily and easily viewed.

A further object resides in the provision of an identification card holder wherein the 15 identification card cannot be removed without breaking the transparent housing, or otherwise disrupting the holder whereby to indicate that the vehicle equipped with the identification card holder is being driven by 20 an unauthorized person.

Still a further object of the invention is to provide a license tag seal that can be readily and easily assembled, means being provided whereby the license tag will be secured 25 against rattling when the present invention is associated with the license tag.

A further object is to provide a license tag seal of the above mentioned character which is simple in construction, inexpensive, strong 30 and durable and further well adapted to the purpose for which it is designed.

Other objects and advantages of the invention will become apparent from the following description when taken in connection with 35 the accompanying drawing.

In the accompanying drawing wherein like reference characters indicate corresponding parts throughout the same:

Figure 1 is a front end elevation of the 40 license tag seal per se.

Figure 2 is a side elevation of the license tag seal showing the manner in which the same is associated with a license tag, an identification card being shown arranged 45 within the holder.

Figure 3 is a longitudinal sectional view through the holder and showing the license tag supporting strap member associated therewith.

Figure 4 is an elevational view of the outer sleeve forming a part of the identification card holder, and

Figure 5 is a similar view of the inner sleeve.

55 In the drawing wherein for the purpose

of illustration is shown the preferred embodiment of my invention, the numeral 1 designates generally my improved license tag seal, the same comprising an elongated sheet metal strip 2 that is bent into substantially 60 U-shaped formation, the bight portion 3 thereof being disposed through a suitable opening 5 provided therefor in the intermediate portion of the license tag 5 so that said arms of the U-shaped member will be disposed 65 on opposite sides of the upper portion of the tag. The innermost arm is formed at its upper end portion with an opening 6 that is adapted to register with an opening 7 formed in the upper edge portion of the 70 license tag 5 and the upper end of the outer arm is also formed with an opening shown at 8 in Figure 3 for a purpose to be presently described.

An elongated bolt 9 extends through the 75 registering openings in the upper ends of the arms of the U-shaped member 2, and the opening 7 formed in the upper edge portion of the license tag 5, the head 10 of this bolt being adapted for engagement with the outer 80 face of the upper end portion of the outer arm of the U-shaped member. The other end of this bolt is formed with a tapered portion 11 that terminates inwardly of the free end of the bolt whereby a shoulder 12 is formed 85 at the juncture of the smaller end of the tapered portion 11 with the free end portion of the bolt as shown very clearly in Figure 3. A nut 13 is threaded on the bolt for disposition between the apertured ends of the arms 90 of the U-shaped member 2, and the manner in which this nut cooperates with the license tag or plate 5 will also presently be described.

As shown in Figure 1, the outer face of the outermost arm of the U-shaped member 2 may 95 have printed or otherwise arranged thereon suitable indicating indicia such as the year for which the license tag is issued.

Also forming a salient part of the present invention is an identification card holder, and the same comprises an outer elongated metallic sleeve 14, the inner end of this sleeve being formed with an outwardly disposed annular flange 15. Secured on the inner end portion of this sleeve 14 in any appropriate manner is the collar 16 that is formed on its outer face at its perimeter, with the flange 17.

The cylindrical sleeve 14 is formed in its intermediate portion with the diametrically opposed spring fingers 18 that extend longi- 110

tudinally with respect to the sleeve and the outer free ends of these spring fingers are disposed inwardly within the cylinder or sleeve to form a restricted passage.

5 The identification card holder further includes the provision of an inner metallic elongated sleeve 19 which is of a smaller diameter than the sleeve 14, and also the inner sleeve is shorter than the outer sleeve and this 10 is clearly illustrated in Figure 3. Formed on the inner end of the inner sleeve 19 is the enlarged head 20, while the other end of the inner sleeve is formed with an outwardly disposed annular flange 21. A collar 22 has its 15 hub portion 23 fixedly secured on the outer end portion of the inner sleeve 19, and an annular flange 24 is formed at the outer edge of the collar.

The collar 22 is formed with a circumferential channel 25 in one face thereof, as shown 20 in Figure 3 for a purpose to be presently apparent.

A pair of longitudinally extending elongated spring fingers 26 is formed in the intermediate portion of the sleeve 19 at diametrically opposite points, and the free ends of these spring fingers are directed inwardly. As shown in the drawing, the free ends of the spring fingers 18 are disposed adjacent the 30 inner end of the card holder while the free ends of the spring fingers 26 are disposed adjacent the outer end portion thereof.

The identification card holder further includes the provision of the cylindrical housing 27 that is open at its respective ends, and this housing is preferably constructed of glass, although any other transparent material may be used. The identification card 28 which contains suitable identification data, 35 such as the name of the owner of the vehicle, the address of the owner and other data pertaining to the vehicle with reference to the serial number of the motor and the like is rolled into tube formation for disposition 40 within the glass cylindrical housing 27.

In assembling the identification card holder, the cylindrical housing 27 with the identification card 28 arranged therein is slipped over the outer metallic sleeve 14 so that the 50 inner end of the housing will engage with the inner face of the collar 16 and will be disposed against the inner face of the annular flange 17. The inner sleeve 19 is then inserted through the outer end of the outer 55 sleeve 14, the head 20 formed on the inner end of the inner sleeve forcing the spring fingers 18 outwardly until the head passes beyond the free ends of the spring fingers 18 whereupon the free ends of the fingers will 60 engage with the inner face of the head to lock the inner sleeve against displacement from the outer end of the outer sleeve, and when 65 in this position the outer end of the glass housing will enter the circumferential channel 25 formed in the collar 22, thereby posi-

tively securing the transparent housing, and the identification card arranged therein in a sealed manner.

The identification card holder as a unit is then slid over the free end portion of the bolt 9, the spring fingers 26 that are associated with the inner sleeve 19 being forced outwardly until the shoulder 12 passes beyond the free ends of these spring fingers whereupon said spring fingers will spring inwardly and engage with the shoulder and the tapered portion 11 to lock the identification card holder on the bolt and the flanged inner end of the sleeve 14 will be in engagement with the inner face of the upper end portion 75 of the adjacent arm of the U-shaped member 2.

By turning the nut 13 in one direction, the same will engage with the outer face of the license tag or plate 5 and will positively clamp 85 the same against the inner arm of the U-shaped member so that rattling of the license tag will be prevented.

It will thus be seen from the foregoing description, that I have provided a license tag seal that can be readily and easily assembled and attached to a tag whereby the tag cannot be removed without disrupting the seal and furthermore the identification card 28 cannot be removed from its holder unless the glass 95 housing is broken, and this will indicate that an unauthorized person is driving the vehicle.

By mounting the identification card in the manner as shown and described, the same will at all times be readily visible for inspection 100 by the proper authorities.

The simplicity of my device enables the same to be manufactured at a very low cost, and furthermore my device will at all times be positive and efficient in carrying out the 105 purposes for which it is designed.

While I have shown the preferred embodiment of my invention, it is to be understood that minor changes in the size, shape and arrangement of parts may be resorted to without departing from the spirit of the invention, and the scope of the appended claims.

Having thus described the invention, what I claim as new and desire to secure by Letters Patent is:

1. In combination, a license tag formed with a pair of spaced openings, a substantially U-shaped member having its bight portion disposed through one of its openings, the arms of the U-shaped member being disposed on opposite sides of the license tag, the free ends of the arms of the U-shaped member being formed with openings registering with the other opening in the license tag, a bolt disposed through the aforesaid registering openings, and an identification card holder secured on the free end of the bolt.

2. In combination, a license tag formed with a pair of spaced openings, a substantially U-shaped member having its bight por-

tion disposed through one of its openings, the arms of the U-shaped member being disposed on opposite sides of the license tag, the free ends of the arms of the U-shaped member being formed with openings registering with the other opening in the license tag, a bolt disposed through the aforesaid registering openings, an identification card holder secured on the free end of the bolt, and a nut 10 threaded on the bolt for disposition between the free ends of the arms of the U-shaped member for securing the license tag in a rigid position.

3. In combination, a license tag formed 15 with a pair of spaced openings, a substantially U-shaped member having its bright portion disposed through one of its openings, the arms of the U-shaped member being disposed on opposite sides of the license tag, the free 20 ends of the arms of the U-shaped member being formed with openings registering with the other opening in the license tag, a bolt disposed through the aforesaid registering openings, an identification card holder secured on the free end of the bolt, and cooperating means between the identification card holder and the bolt for permanently securing the holder on the bolt.

4. An identification card holder comprising 30 in combination inner and outer sleeves, a cylindrical transparent housing for an identification card encircling the outer sleeve, flanged collars on the inner and outer ends of the outer and inner sleeves respectively for 35 engagement with the respective ends of the transparent housing, and cooperating means between said sleeves for securing the same together against sliding movement to lock the flanged collars in engagement with the transparent housing.

5. An identification card holder comprising 45 in combination inner and outer sleeves, a cylindrical transparent housing for an identification card encircling the outer sleeve, flanged collars on the inner and outer ends of the outer and inner sleeves respectively for 50 engagement with the respective ends of the transparent housing, and cooperating means between said sleeves for securing the same together against sliding movement to lock the flanged collars in engagement with the transparent housing, said means including an inwardly disposed spring finger carried by the outer sleeve, and a shoulder on the inner 55 sleeve with which the free end of the spring finger engages.

6. An identification card holder comprising

ing in combination inner and outer sleeves, a cylindrical transparent housing for an identification card encircling the outer sleeve, 60 flanged collars on the inner and outer ends of the outer and inner sleeves respectively for engagement with the respective ends of the transparent housing, cooperating means between said sleeves for securing the same together against sliding movement to lock the flanged collars in engagement with the transparent housing and means for attaching the card holder to a support.

7. An identification card holder comprising 70 in combination inner and outer sleeves, a cylindrical transparent housing for an identification card encircling the outer sleeve, flanged collars on the inner and outer ends of the outer and inner sleeves respectively 75 for engagement with the respective ends of the transparent housing, cooperating means between said sleeves for securing the same together against sliding movement to lock the flanged collars in engagement with the transparent housing, means for attaching the card holder to a support, said attaching means including a bolt extending through the support, and disposed within the inner sleeve, and cooperating means between the bolt and 80 the inner sleeve to lock the card holder against sliding movement with respect to the bolt in one direction.

8. An identification card holder comprising 85 in combination inner and outer sleeves, a cylindrical transparent housing for an identification card encircling the outer sleeve, flanged collars on the inner and outer ends of the outer and inner sleeves respectively for 90 engagement with the respective ends of the transparent housing, cooperating means between said sleeves for securing the same together against sliding movement to lock the flanged collars in engagement with the transparent housing, and means for attaching the 95 card holder to a support, said attaching means including a bolt extending through the support, and disposed within the inner sleeve, and cooperating means between the bolt and the inner sleeve to lock the card holder 100 against sliding movement with respect to the bolt in one direction, the last mentioned means comprising an inwardly disposed spring finger carried by the inner sleeve, and a shoulder formed on the bolt with which the 105 free end of the spring finger engages.

In testimony whereof I affix my signature.

LUTHER J. KIGER.
